UNITED STATES PATENT OFFICE.

CHARLES J. STEINAU, OF NEW YORK, N. Y.

DESIGN FOR A DISPLAY-CARD.

No. 37,717.

Specification for Design.

Patented Dec. 5, 1905.

Application filed October 10, 1905. Serial No. 282,213. Term of patent 3½ years.

To all whom it may concern:

Be it known that I, CHARLES J. STEINAU, a citizen of the United States, and a resident of the city of New York, borough of Manhattan, in the county and State of New York, have invented a new, original, and ornamental Design for a Display-Card, reference being had to the accompanying drawing.

The figure is a plan view of a show-card, showing my new design.

I claim—

The ornamental design for a display-card as shown.

CHARLES J. STEINAU.
